UNITED STATES PATENT OFFICE

2,568,281

COAXIAL LINE STUB SUPPORT

Joseph Goldsmith, Newton, Mass., assignor to
 Raytheon Manufacturing Company, Newton,
 Mass., a corporation of Delaware

Application February 15, 1944, Serial No. 522,489

5 Claims. (Cl. 178—44)

1

This invention relates to coaxial transmission lines, and more particularly to a novel means for supporting the central conductor of such lines in proper alignment with the surrounding outer conductor.

Heretofore various means have been proposed for supporting the central conductor of a coaxial line relative to the outer conductor. One of the most common means involves the use of insulating disks or beads through which the central conductor extends, and which have a tight fit within the outer conductor. Such constructions introduce dielectric losses and electrical discontinuities in the line due to the difference in the dielectric constant of the insulating disks and the air between the disks. Furthermore, such lines are not simple in construction since the disks must be spaced at predetermined distances apart and it is difficult to prevent displacement of the disks along the line. In cases where the line must extend vertically, as for example to an elevated antenna structure, the disks must be rigidly fixed with respect to the transmission line.

To avoid such difficulties, it has been proposed to support the central conductor by means of stub supports, each stub constituting a branch line having a length approximately equal to one-quarter of the length of the waves on the transmission line. Such stub supports, while affording satisfactory alignment of the central conductor, possess many disadvantages. Inasmuch as the stub lines project beyond the circumference of the outer conductor for a substantial distance, the overall dimensions of the transmission lines are greatly increased and its bulk and weight become excessive. Due to the many stub lines projecting radially in all directions from the transmission line, the line becomes difficult to install in any place where space is a material consideration.

It is among the objects of the invention to avoid the difficulties inherent in conventional structures of the type described and to provide a structure which obviates the necessity for introducing supporting disks of dielectric material into the transmission line or for providing numerous stub lines projecting therefrom.

It is also among the objects of the present invention to provide a high frequency transmission line capable of transmitting waves of high frequency over a relatively wide frequency range without substantial differences in the attenuation of the waves.

It is a further object of the invention to provide a high frequency transmission line which is

2

simple in construction and manufacture, and in which the alignment of the two conductors is maintained with great rigidity and at a substantial saving in weight and a decrease in bulk and cost of manufacture, as compared with conventional transmission lines of the coaxial type.

The above and other objects of the invention will be made apparent to those skilled in the art from a consideration of the following detailed description taken in conjunction with the accompanying drawing in which:

Fig. 1 represents a longitudinal section through a portion of a coaxial transmission line constructed in accordance with the present invention; and

Fig. 2 represents a transverse section taken on the line 2—2 of Fig. 1.

In the drawing reference numeral 1 indicates a section of the outer tubular conductor of a coaxial transmission line having a central conductor 2. At points where the central conductor is to be supported by the outer conductor, a portion of the outer conductor 1 is cut away and a block 3 is inserted in the opening so formed, which block 25 partially obstructs the free space between the outer conductor 1 and the inner conductor 2. The block 3 is of conductive material and is rigidly connected to the outer conductor 1, as, for example, by soldering, and completely closes the opening in the outer conductor 1. A screw bolt 4 extends through the block 3 and is threaded into an insert 5 secured in the central conductor 2 at an enlarged portion 6 thereof. The enlarged portion 6 extends for a distance approximately 30 equal to one-half of the length of the waves on the transmission line. The insert 5 is of conductive material and is secured to the conductor 2 at the enlarged portion 6 in a manner to provide both a good electrical and rigid mechanical connection therewith. The insert 5 is of substantially the same diameter as the unenlarged portion of the conductor 2 and constitutes a rigid metallic connector functioning as a branch from conductor 2 electrically connected to the conductor 1 at the block 3. A good electrical connection may be secured between the insert 5 and block 3 by soldering the joint therebetween after the parts have been secured in position by the bolt 4.

It has been found that the construction described provides substantially reflectionless transmission of high frequency waves covering a relatively wide range of frequencies and will transmit power of the order of one megawatt without break-down. For example, in a fifty ohm line

of one and one-half inches inside diameter designed to transmit frequencies in a region of 3000 mc., a frequency range of 60 mc. was transmitted without reflections and without substantial differences in the attenuation of the waves at all transmitted frequencies and without breakdown at 0.75 megawatt indicating that power in excess of this value may be transmitted.

It will be understood that the shape of the inner supports may be varied in wide limits and dimensioned to suit the particular portion of the high frequency spectrum employed. In any particular case the impedance provided by the enlargement 6 or equivalent element on the conductor 2 and by the block 3 or equivalent element on the conductor 1 will be proportioned to match under the particular operation conditions and cancel out reflections resulting from the support to secure substantially reflectionless transmission within the frequency range which the line is adapted to transmit.

In the determination of the dimensions of the parts for any particular frequency range, it will be simpler in most instances for those skilled in the art to determine these by direct electrical measurement of reflection than to predetermine them by analysis. In making such determinations, it will be helpful to consider the functions of the enlargement 6 separately from its functions in combination with the block 3. If a direct connection is made between the conductor 2 and the conductor 1 by a branch connector such as 5, without the enlargement 6 and without the block 3, for substantially all frequencies the impedance along the connector is not infinite and there will be reflections from the connector. When an enlargement 6 is provided extending for approximately one-quarter wave length on each side of the center of the connector 5, then some of the reflections are cancelled even without the impedance provided by the block 3. Under these conditions the enlargement 6 functions as a transformer to greatly increase the impedance and substantially decrease the reflections, or, in other words, to introduce a compensating impedance tending to match the impedance introduced by the connector 5, and thus tending to make the lumped impedance of the connecting structure infinite. Where the transformer 6 does not produce an infinite lumped impedance, the block 3, or some equivalent impedance, is provided in addition to the enlargement 6. Under these conditions the impedance becomes infinite and there will be no reflections. Thus, the enlargement 6 and the block 3 function as matching impedances, and when matched to the impedance introduced by the connector 5, the impedance across the line becomes infinite while substantially no impedance is offered by the support in the direction of the line.

Thus, while the enlargement 6 may of itself reduce the electrical discontinuities introduced in the line by the branch connector 5, I prefer to supply a coaxing impedance, such as block 3, in the preferred arrangement shown.

As an example of the preferred arrangement, in one commercially successful embodiment of the invention, in a line operating upon a wave length of 9.8 centimeters, the following dimensions were used. The internal diameter of the conductor 1 was 1.527", the diameter of the central conductor was $\frac{5}{8}$ ", the diameter of the enlargement 6 was 0.779", and its length was 1.950". The length of the block 3 in the direction of the line was

1.250". This projected into the line for a maximum distance of 0.287".

It will be observed that because of the great mechanical strength and rigidity of the support, only a few such supports need be provided along a substantial length of the transmission line in order to secure and maintain the desired alignment of the conductors. Thus, unlike prior constructions, but a small number of supports are essential. However, where desired, the supports may be spaced one-half wave length apart or at any distance greater than one-half wave length.

It will be obvious that many departures may be made from the specific details shown. For example, the enlargement 6 need not be formed integral with the line 2 but may be formed as a separate sleeve and shrunk on or otherwise secured in intimate contact with the conductor 2. Similarly parts such as the insert 5 may, where convenient, be formed integrally with the conductor 2 or the enlargement 6.

While I have shown a particular embodiment of the invention, other embodiments and modifications within the scope of the appended claims will be apparent to those skilled in the art from a consideration of the structure shown and teachings herein.

What is claimed is:

1. An electric transmission line for transmitting high frequency electric waves including a tubular conductor, a central conductor coaxial with said tubular conductor, means for maintaining said conductors in fixed spaced relation comprising a metallic connector between said conductors, said central conductor having an enlargement thereon, and means projecting inwardly from said tubular conductor partially obstructing the space between said conductors for cancelling reflections resulting from said connector.
2. An electric transmission line for transmitting high frequency electric waves including a tubular conductor, a central conductor coaxial with said tubular conductor, means for maintaining said conductors in fixed spaced relation comprising a metallic connector between said conductors, said central conductor having an enlargement thereon extending for a distance approximately equal to one-half of the length of the waves on said transmission line, said connector being connected to said central conductor at said enlargement, and means projecting inwardly from said tubular conductor for partially obstructing the space between said conductors, said projection and said enlargement being proportioned to substantially cancel the reflection resulting from said connector.

3. An electric transmission line for transmitting high frequency electric waves including a tubular conductor, a central conductor coaxial with said tubular conductor, said tubular conductor having an opening therein, a block rigidly connected to said tubular conductor closing said opening and partially obstructing the space between said conductors, said central conductor having an enlargement thereon, and means providing a supporting connection between said block and the enlarged portion of said central conductor.

4. An electric transmission line for transmitting high frequency electric waves including a tubular conductor, a central conductor coaxial with said tubular conductor, said tubular conductor having an opening therein, a metallic block rigidly connected to said tubular conductor closing said opening and partially obstruct-

ing the space between said conductors, said central conductor having an enlargement thereon and extending for a distance approximately equal to one-half of the length of the waves on said transmission line, and a metal connector of substantially the same diameter as said central conductor providing a supporting connection between said block and the enlarged portion of said central conductor.

5. An electric transmission line for transmitting high frequency electric waves including a tubular conductor, a central conductor coaxial with said tubular conductor and having an enlargement thereon, a metallic connector between said tubular conductor and said enlargement for maintaining said conductors in fixed spaced rela-

tionship, said connector including portions extending inwardly from said tubular conductor toward but terminating in spaced relation to said inner conductor for preventing reflections resulting from said connector.

JOSEPH GOLDSMITH.
